PROCESS FOR PRODUCING PETROLEUM
SULPHONATES

John R. Averill, Webster Groves, Mo., and Edwin E. Claytor, Long Beach, Calif., assignors to Petrolite Corporation, Ltd., Wilmington, Del., a corporation of Delaware

No Drawing. Application September 6, 1940,
Serial No. 355,610

7 Claims. (Cl. 260—504)

This invention relates to a novel process for producing mineral oil sulphonates from petroleum, mineral oil, suitably selected fractions or distillates thereof, or extracts obtained therefrom, by the use of sulphonating agent, such as fuming sulphuric acid or oleum. The process involves subsequent separation of the petroleum sulphonic acid salts, unreacted oil, and unreacted acid in the form of salts, and is further characterized by the separation of a material commonly known as "polymers," "acid sludge," "acid," "pepper," "peppery sludge," etc. This last mentioned product or material is removed in the conventional procedure for manufacturing sulphonic acids or sulphonates by pretreatment with acid such as sulphuric acid.

Our invention is more specifically concerned with the employment of a raw material of the kind characterized by having present polymerizable or sludge-producing constituents of the kind which ordinarily would be eliminated by pretreatment, i. e., adding 2-10% of sulphuric acid of varying strength, for instance, 80-100% sulphuric acid, to the raw material, mixing thoroughly, and subsequently permitting settling to take place. Although pretreatment is the conventional method employed in the manufacture of mineral oil sulphonic acid or sulphonates, it is objectionable for a number of reasons. In the first place, pretreatment involves a distinct and separate step. In the second place, the withdrawal of the acid sludge or polymers involves the accompanying loss of a certain amount of oil. Thirdly, pretreatment is apt to cause the formation of a certain amount of oil-soluble petroleum sulphonlic acids which remain in the pretreated oil, and which must be removed at some subsequent stage. This last statement in regard to oil-soluble sulphonic acids or sulphonates as objectionable impurities in top oil can be readily appreciated when one notes that the production of sulphonic acids or sulphonates, whether by conventional procedures, or by the process herein described, results in a substantial portion of top oil or unreacted oil, which oil, for purposes of economy, must find utility elsewhere, i. e., as a lubricating oil stock, fuel oil, or the like; and for this reason the top oil or the unreacted oil must be substantially free from oil-soluble sulphonic acids, or sulphonates, even though the amount of the recovered sulphonic acids or sulfonates is relatively small.

One of the main objects of our invention is to eliminate pretreatment as a separate step in

the production of petroleum sulphonates. To this end we have devised a process in which a single sulphonation step is employed to produce both the sulphonic acids and the polymerized material commonly referred to as peppery sludge, pepper, or the like. As to a more complete description of such peppery sludge or similar materials, reference is made to U. S. Patent No. 1,947,861, dated February 20, 1934, to 10 Liberthson.

Another important object of our invention is to eliminate the peppery sludge as such, without being admixed with accompanying unreacted oil and the like, thus affording an additional 15 economy.

Still another object of our invention is to obtain the advantages previously enumerated, to wit, avoid pretreatment and eliminate the peppery sludge subsequently free from accompanying unreacted oil, and at the same time recover the unreacted oil substantially free from mahogany acids or sulphonates, and for that matter free from peppery sludge, and which accordingly, is readily utilizable for any suitable purpose.

The fourth object of our invention is to accomplish the three objectives aforementioned and simultaneously eliminate substantially all peppery sludge and inorganic salts, so as to yield 20 a suitable solution of sulphonates substantially free from peppery sludge, sodium sulphate or the like. In view of the subsequent description of the procedure employed in carrying out our process, it will be obvious that there are numerous 25 other advantages, hereinafter pointed out, which make the process particularly rapid and economical.

Specifically, we have discovered that a solution 30 of green acid sulphonates in a tertiary mixture of ethyl alcohol, isopropyl alcohol, and water has the characteristic property of extracting substantially all mahogany acid sulphonates from the unreacted oil, without dissolving any of said oil in said sulphonate mixture and without itself 35 dissolving appreciably in the unreacted oil, and furthermore, is devoid of any solvent properties in respect to inorganic sulphate, such as ammonium sulphate and the like. A solution of 40 sulphonates of the kind described does not act either as a solvent or suspending agent for the peppery sludge, and the procedure that we employ results in polymers or peppery sludge substantially de-oiled, i. e., free from any adherent oil in a form which represents a feathery inter- 45

55

face, suspension, or loose emulsion in the aqueous solution of inorganic sulphates or the like.

The effectiveness of the present procedure is made possible primarily by the employment of the aqueous solution of a mixture of ethyl and isopropyl alcohol. The results obtained, and in fact, the application of the procedure herein described, would be impossible, except by means of a solvent of the kind selected. This may be illustrated by the fact that if one attempts to substitute isopropyl alcohol, or an aqueous solution thereof, for the alcoholic mixture herein employed, there results an unsatisfactory separation, due to the solubility of unreacted oil in the alcoholic solution of the sulphonates and of alcohol in the unreacted oil. Thus, one obtains a sulphonate extract which is contaminated with an excess or objectionable amount of unreacted oil, and which is of an inferior quality, or which must be treated subsequently so as to separate or extract the unreacted oil. Other solvents which might otherwise work are unsatisfactory, on account of their higher cost and greater fire hazard. It will be recalled that one of the principal objects of the present invention is to apply a single sulphonation step, a single washing step, and a single separatory step involving a neutralized material; whereas, conventional pro-
5 rial, i. e., raw material containing polymerizable cedure employing the same kind of raw mate-
6 components, invariably includes pretreatment and sulphonation, i. e., two distinct steps in which acid or oleum is involved, and usually includes four distinct steps in regard to separation: the conventional washing operation, neutralization, a step involving the alcoholic extraction of mahogany acids or salts from the unreacted oil, or, inversely, the extraction of unreacted oil from a mixture of sulphonates, and another step in which inorganic salts are removed from the sul-
7 phonates.

For this reason, in order to obtain the results desired, it is not satisfactory to employ a solution of isopropyl alcohol, because one does not attain the primary objects of the present invention. Similarly, an effort to employ a solution of ethyl alcohol is not feasible, for the reason that ethyl alcohol does not yield a substantial or complete separation of inorganic salts in the form of a highly concentrated solution. Incidentally, the same is true in regard to methyl alcohol. We wish it to be understood that references herein to ethyl alcohol, are intended to include, for example, denatured alcohol, and particularly, the type which is essentially a mixture of 90 parts of ethyl alcohol and 10 parts of methyl alcohol.

In view of what has been said, it will be appreciated that the present process involving a single sulphonation step, a single washing step, and a single separatory step, involving neutral or substantially neutral material, yields a mixture of sulphonates of unusual purity and also a resultant top oil or unreacted oil of unusual purity. Indeed, in these three principal steps, we accomplish substantially the same results that heretofore have been accomplished by four or five separate steps.

The actual operative steps employed in practising our process are obvious, in view of what has been said previously. The first step is to select a suitable raw material. Raw materials suitable for carrying out this process are characterized by presence of a significant amount of materials which produce a peppery sludge or

75 polymers. Generally speaking, such raw materials are the kind in which the molecular constituents themselves contain eight carbon atoms or more. They are also of the kind which have

5 a substantial portion of sulphonatable materials, i. e., probably at least 10-15%, and possibly as much as 65% of material which can be converted into green sulphonic acids with a greater or lesser amount of mahogany sulphonic acids. Particularly desirable raw materials are exemplified by 10 non-pretreated Gulf Coast lubricating distillate having a Saybolt Universal viscosity at 100° F. of about 400 seconds; or one may employ any suitable petroleum crude, such as Peruvian, 15 Colombian, Russian, Californian, Ranger Burbank, Mid-Continent, etc. When employing crude oils, rather than any distilled fractions thereof, our preference is to employ Gulf coastal crude of the type which is essentially naphthene 20 in nature. As to suitable raw materials, reference is made to the aforementioned patent to Liberthon, and also to U. S. Patent No. 2,115,847, dated May 3, 1938, to Gohr; U. S. Patent No. 2,084,506, dated June 22, 1937, to Rosen, and U. S. 25 Patent No. 2,188,770, dated January 30, 1940, to Robertson.

The actual step of sulphonation, or rather, the combined sulphonation-polymerization step, is identical with the conventional sulphonation step 30 employed in the sulphonation of pretreated materials obtained from the same source; but it is to be remembered that in the present instance such pretreatment is eliminated and the sulphonation step simultaneously involves polymerization, i. e., the production of pepper or peppery sludge. The four patents previously referred to describe suitable conditions for sulphonation; but it is our experience that the most desirable conditions for sulphonation may be indicated by the 35 following approximate range:

Our preference is to use oleum in substantially every instance. The oleum will vary from 10% excess SO_3 , to 35% excess SO_3 ; and we preferably use commercial oleum, representing approximately 20% excess SO_3 . The amount of oleum employed per unit weight of hydrocarbon material depends upon the percentage of material to be sulphonated in the total, its molecule weight and ease of sulphonation. Needless to say, as 45 the strength of oleum decreases below 20% free SO_3 , one necessarily must increase the amount employed to obtain the same result; and if one employs an oleum of a higher concentration, for instance, 30% oleum, one may employ a lesser amount. On weight basis, the oleum may vary 50 from 20% or less to 300%, or even more.

It is understood that reference to various amounts of oleum is not intended to indicate that experimentation is necessary, in order to 55 find some critical conditions of sulphonation that make the present process possible. The strength or amount of oleum or sulphonating agent employed is not critical. It is the amount indicated by conventional sulphonation procedure. However, as is readily understood by those skilled in the art, the use of excessive amounts of oleum is costly, because of

- (a) The expense of the oleum itself with decreased yield on the basis of oleum used;
- (b) A longer time required to add the oleum;
- (c) A greater tendency towards oxidation;
- (d) Increased cost due to amount of wash water required and increased amount of waste acid to be disposed of.

70 Thus, for purposes of economy, one uses the

minimum amount justified on the yield of sulphonate. In other words, the use of an increased amount of oleum might yield a larger amount of sulphonate; but such procedure might be uneconomical. As has been repeatedly emphasized, the novelty of the invention herein described lies in the purification steps subsequent to sulphonation. Although polymerization is included with sulphonation, the amount of acid used in the step of sulphonation is not altered by use of the method described herein.

The temperature employed during reaction may vary from any suitable temperature which permits sulphonation to take place at a suitable rate and in suitable yield, for instance, 0° F., to any temperature short of the point where rapid oxidation takes place, as indicated by the liberation of excessive amounts of sulphur dioxide or the like. Generally speaking, the upper range for the sulphonating temperature is roughly 205-210° F., i. e., just short of the boiling point of water. This varies somewhat with the particular raw stock selected, strength of oleum, ratio of oleum to raw stock, etc.; and in some instances, one may even employ a temperature exceeding the boiling point of water. Roughly speaking, 70-110° F., appears to be a very suitable temperature of sulphonation, it being understood, of course, that polymerization is simultaneously involved.

The time of reaction is directly related to the batch size, container employed, mixing device, temperature of sulphonation, etc. Generally speaking, the time employed automatically is determined by the addition of a sulphonating agent at such a rate as not to exceed a predetermined temperature range; for instance, one adds the oleum at such a rate as not to exceed a temperature of 70-110° F., if this has been predetermined as the most suitable temperature. Here again, the time of sulphonation would be directly affected by the presence or absence of cooling coils, the effectiveness of such cooling coils, etc. As has been previously suggested, this particular item represents nothing more than conventional sulphonation procedure employed in connection with similar pretreated stock.

The step of washing the sulphonated mass, i. e., treating the sulphonated mass with wash water or with a saline solution in order to separate unreacted acid, is conducted in the conventional manner to leave behind as little uncombined acid as possible and not yield an excessive amount of draw-off waste or acid water. Generally speaking, the rule is to add sufficient water or saline solution so as to dilute the draw-off acid to a strength of approximately 50-80% H₂SO₄. This washing step, again, is the conventional step employed in sulphonating similar material after pretreatment.

After such sulphonation involving simultaneous polymerization, and after the conventional washing step, we employ the novel step of the kind previously indicated, and which is now described in detail. The washed acidic mass obtained in the manner above described is next neutralized with any suitable base, such as caustic soda, caustic potash, ammonia, or an amine, which forms a water-soluble salt. A base of the kind described may be indicated as a "base forming a water-soluble salt." For purposes of economy and in view of increased solubility of the resulting salts, we prefer to use ammonia, i. e., ammonium hydroxide of commerce, or 26° Bé. strength. The amount added under

5 suitable conditions of agitation is sufficient to make the acidic mass just neutral to methyl orange. One might neutralize to a lesser degree; i. e., free acidity may be present, provided there is complete separation from the sulphonate of inorganic salts and free mineral acid. The next step is to add an alcohol solution of the kind subsequently described, and in such a manner so that the green sulphonates can dissolve in the 10 alcoholic solution and the combined mixture or solution has an ample opportunity to act as a solvent or extractive for the mahogany sulphonates dissolved in the unreacted oil.

Thus, the next step is to decide on the proper 15 alcoholic solution and ratio to be employed in combination with the neutralized or substantially neutralized mass. As has been previously indicated, the alcohols employed are isopropyl alcohol and ethyl alcohol, the expression "ethyl alcohol" being intended to include denatured alcohol which may contain approximately 10-15% of other materials of the kind commonly employed as denaturants, provided that such denaturants are compatible with the procedure outlined. For 20 purposes of economy, we prefer to use denatured alcohol containing 90% ethyl alcohol and 10% methyl alcohol. For practical purposes, this will be considered as if it were 100% ethyl alcohol.

The mixture employed consists of approximately 30 one-third each isopropyl alcohol, ethyl alcohol, and water. The actual percentages of any individual component is within the ratio of 20% and 55%. It must be remembered that the ratio of the alcohols to each other is approximately 35 1-1, or within the ratio of approximately 60-40 and 40-60. Ordinarily speaking, the percentage of water in the neutralized mass approximates 15-20%. If, however, one obtains a neutralized mass with an excessive amount of water, for instance, 25-35%, obviously one would make 40 an appropriate reduction in the amount of water added to the alcohol mixture. It is to be noted that the process as indicated removes inorganic salt in the form of a solution and not as undissolved crystals, i. e., as an insoluble liquid bottom layer. Obviously, one must attempt to obtain the most concentrated solution possible, without the presence of undissolved crystals. For this 45 reason, the amount of inorganic salts to be removed as a concentrated solution and the amount of water present, are factors in determining the amount and ratio of aqueous alcohol solution to add to the neutralized mass. Use of too little water has the dual disadvantage of causing the 50 alcohols to throw inorganic salts out as solids and to allow excessive solution of the alcohols in the unreacted oil. It is to be noted that the ratio of alcohols to each other and the percentage of water to be added must be predetermined with reasonable accuracy; but when once 55 determined, such procedure can be employed indefinitely without further change, provided that sulphonation conditions and subsequent steps remain the same. Actually, a person skilled in the 60 art appreciating the various steps that are herein accomplished, could readily determine the ratios of solvents and water without detailed directions. However, even at the expense of verbosity, such directions for predetermination are included.

It is our preference to make mixtures of denatured ethyl alcohol and isopropyl alcohol in the ratios of 40-60, 50-50, and 60-40. Having obtained these three binary mixtures, we prefer to

make solutions in water form of each binary mixture in the following ratios:

Alcohol mixture	Water
Percent	Percent
80	20
75	25
70	30
65	35
60	40
55	45
50	50

Thus, one obtains 21 alcoholic solutions of varying compositions and strength.

The amount of alcoholic solution employed varies from approximately a weight equal to the neutralized mass, up to and equal to 150% thereof. In actual practice one must use an amount of the alcoholic solvent equal to at least one-half the weight of the neutralized mass and not more than an amount equal to twice such weight. Thus, having obtained the 21 solutions aforementioned, one simply makes a series of cut and try experiments with representative samples of neutralized mass, using an equal volume and also 50% excess. The first series of such 42 tests will immediately and conclusively indicate substantially the best mixture of alcohols in relation to each other, the best dilution with water and approximately the best ratio to use in proportion to the neutralized mass. Subsequent minor variations can be made to indicate optimum conditions for any specific set of conditions.

Experiments of the kind above described may be conducted in any convenient manner. Visual examination readily reveals conditions which eliminate the bulk of inorganic salt brine along with the peppery sludge. Unreacted oil can be examined in the conventional manner for the presence of mahogany sulphonate salts. The middle layer of sulphonates can readily be examined for the presence of either inorganic salts or unreacted oil. Experiments which appear to indicate the best conditions or minor variations thereof can readily be repeated in large size separatory funnels or centrifuge tubes and rechecked with greater accuracy and convenience. The methods for examination or analyses of petroleum sulphonate acids and their salts are well known; but for convenience, reference is made to "Sulphated Oils and Allied Products," by Burton and Robertshaw, 1940, Chemical Publishing Co., Inc., page 155 et seq.

We are fully aware that the procedure herein described may be of definite value in refining procedure where the primary object is not to obtain sulphonates, but to obtain a suitable refined petroleum product in which the removal of the sulphonates is an incidental step, rather than the primary object. The sulphonates herein described may, of course, be used for any purpose for which this type of material is conventionally employed, for instance, resolution of water-in-oil type emulsions, the manufacture of oil-in-water emulsions, wetting agents, spray oils, cutting oils, road oils, and the like.

In employing such procedure, whether experimentally in laboratory glassware or in plant operation, as will be illustrated by subsequent example, one obtains a separation in which the unreacted oil is substantially free from peppery sludge and from sulphonate acids or sulphonates. One obtains an alcoholic solution of a mixture of

green and mahogany sulphonates, with the green acid sulphonates predominating substantially free from (a) unreacted oil; (b) peppery sludge; and (c) inorganic sulphates. The peppery sludge appears in the draw-off brine either as a feathery layer, or suspension, or as a loose emulsion. The unreacted oil is separated and employed for any suitable purpose; the draw-off brine is withdrawn and may be used for some other purpose, if desirable; i. e., if it consists primarily of ammonium sulphate, it might be freed from sludge and used for fertilizer or other purposes. An alcoholic solution of the green and mahogany sulphonates may be employed as is, or may be freed from alcohol and excess water by the usual distillation procedure. The alcohol solution, which is recovered, of course, may be employed in a subsequent cycle. It is to be emphasized that previous reference to a sulphonating agent, such as oleum, is for purpose of illustration only, and that any suitable sulphonating agent, such as 100% sulphuric acid, SO_3 , or the like might be employed. Similarly, chlorosulphonic acid or other suitable sulphonating agents may be employed. Oleum is, however, most desirable from the standpoint of rapid sulphonation and low cost.

It need not be remarked that the previous step of neutralization, followed by dilution with the alcoholic solution, may be varied in the respect that the alcoholic solution may be added first and the neutralizing agent afterwards, or both might be added simultaneously. In other words, neutralization and addition of solvent solution, together with agitation required for extraction, may conveniently be considered as a single step. It is understood that the hereto attached claims are not intended to be limited in regard to whether neutralization is employed first or dilution first, or if the two procedures are employed simultaneously, unless such claims recite specific conditions involving such procedures.

It is to be emphasized that the addition of the aqueous alcoholic solution is not merely dilution, but is in essence an extraction process in which the alcoholic solution with the dissolved green acid sulphonate extracts the mahogany sulphonates present in the unreacted oil. For this reason, both in the laboratory procedure outlined and in actual plant operation, the addition of the aqueous alcoholic solution must be followed by thorough and vigorous mixing treatment of such duration as to permit extraction to take place. In other words, mere dilution and immediate settlement are unsatisfactory.

A suitable procedure for the preparation of these mixed sulphonates of good grade, is illustrated in the following example:

Example

4,000 lbs. of crude naphthalene base Gulf Coast oil are mixed with 2,000 lbs. of 20% oleum while keeping the temperature below 30° C. This takes 2½ hours approximately. The batch is stirred for 45 minutes after the last of the acid has been added. Then this non-homogenous mass is washed with 1,000 lbs. of water, stirring well, and the acid water settled out at 80° C. in 3½ hours. After withdrawal of the bottom layer, the remainder, consisting of a layer of green acids and a layer of unreacted oil containing mahogany acids is cooled to 40° C. and then neutralized with ammonia to methyl orange while keeping the temperature below 50° C. The impure sulphonate mixture is thereupon pumped into a large

tank which contains a mixture of 840 lbs. denatured alcohol, 840 lbs. isopropyl alcohol, and 1,000 lbs. water (sp. gr. 0.8894), i. e., proportions of 31.3%, 31.3%, and 37.4%, respectively. After stirring well, the mixture is allowed to settle overnight. The bottom layer containing the inorganic sulphates and water (sp. gr. 1.18-1.19) together with the semi-emulsified "peppery sludge" or "polymers" is drawn off. The middle layer which contains the ammonium salts of the green acids and the mahogany acids is sent to a still, where about 48% of the charge by weight is distilled off. The material remaining in the still after distillation is a commercial standard product which has various uses, among which is its wide applicability for resolving petroleum emulsions.

This invention is not to be limited by the example or specific description which has been presented herein solely by way of illustration. It is our intention that the invention be limited only by the appended claims, in which we have endeavored to claim all novelty which our process permits. In the claims where the term "alkali" is used, it is intended to embrace ammonium and substituted ammoniums, as well as the alkali metals.

Having thus described our invention, what we claim as new and desire to secure by Letters Patent is:

1. A process for producing petroleum sulphonates, characterized by subjecting a member of the class consisting of non-pretreated crude petroleum, non-pretreated mineral oil, non-pretreated petroleum distillate, and non-pretreated mineral oil extract containing a significant amount of polymerizable constituents to the following procedure; (a) a sulphonation-polymerization step; (b) a washing step involving an aqueous vehicle and subsequent separation of dilute acid; (c) a neutralization-alcoholic solvent addition-extraction step involving neutralization by means of a soluble salt-forming base and the addition of a predetermined amount of an ethyl alcohol-isopropyl alcohol-water mixture in which the percentage composition of the components has been predetermined, said percentage composition in regard to each component being within the range of not less than 20% and not more than 55% by volume and said addition being made so that the added aqueous alcohol solution is not less than one-half the weight and not more than twice the weight of the neutralized sulphonate; (d) permitting said previously agitated diluted mass to separate into a three-layer system consisting of: (A) unreacted oil substantially free from mahogany acid sulphonates and peppery sludge; (B) an aqueous alcohol solution of petroleum sulphonates substantially free from unreacted oil, inorganic acid salts, and peppery sludge; and (C) a substantially concentrated salt brine containing loosely commingled peppery sludge; and (e) withdrawing said aforementioned (A) layer and (C) layer.

2. A process for producing petroleum sulphonates, characterized by subjecting a member of the class consisting of non-pretreated crude petroleum, non-pretreated mineral oil, non-pretreated petroleum distillate, and non-pretreated mineral oil extract containing a significant amount of polymerizable constituents to the following procedure: (a) a sulphonation-polymerization step; (b) a washing step involving an aqueous vehicle and subsequent separation of dilute acid; (c) a neutralization-alcoholic sol-

vent addition-extraction step involving neutralization by means of an inorganic soluble salt-forming base and the addition of a predetermined amount of an ethyl alcohol-isopropyl alcohol-water mixture in which the percentage composition of the components has been predetermined, said percentage composition in regard to each component being within the range of not less than 20% and not more than 55% by volume and said addition being made so that the added aqueous alcohol solution is not less than one-half the weight and not more than twice the weight of the neutralized sulphonate; (d) permitting said previously agitated diluted mass to separate into a three-layer system consisting of: (A) unreacted oil substantially free from mahogany acid sulphonates and peppery sludge; (B) an aqueous alcohol solution of petroleum sulphonates substantially free from unreacted oil, inorganic acid salts, and peppery sludge; and (C) a substantially concentrated inorganic salt brine containing loosely commingled peppery sludge; and (e) withdrawing said aforementioned (A) layer and (C) layer.

3. A process for producing sulphonates, characterized by subjecting non-pretreated crude petroleum containing a significant amount of polymerizable constituents to the following procedure; (a) a sulphonation-polymerization step; (b) a washing step involving an aqueous vehicle and subsequent separation of dilute acid; (c) a neutralization-alcoholic solvent addition-extraction step involving neutralization by means of an inorganic soluble salt-forming base and the addition of a predetermined amount of an ethyl alcohol-isopropyl alcohol-water mixture in which the percentage composition of the components has been predetermined, said percentage composition in regard to each component being within the range of not less than 20% and not more than 55% by volume and said addition being made so that the added aqueous alcohol solution is not less than one-half the weight and not more than twice the weight of the neutralized sulphonate; (d) permitting said previously agitated diluted mass to separate into a three-layer system consisting of: (A) unreacted oil substantially free from mahogany acid sulphonates and peppery sludge; (B) an aqueous alcohol solution of petroleum sulphonates substantially free from unreacted oil, inorganic acid salts, and peppery sludge; and (C) a substantially concentrated inorganic salt brine containing loosely commingled peppery sludge; and (e) withdrawing said aforementioned (A) layer and (C) layer.

4. A process for producing petroleum sulphonates, characterized by subjecting non-pretreated, Gulf coastal naphthene base, crude petroleum containing a significant amount of polymerizable constituents to the following procedure: (a) a sulphonation-polymerization step; (b) a washing step involving an aqueous vehicle and subsequent separation of dilute acid; (c) a neutralization-alcoholic solvent-addition-extraction step involving neutralization by means of an inorganic soluble salt-forming base and the addition of a predetermined amount of an ethyl alcohol-isopropyl alcohol-water mixture in which the percentage composition of the components has been predetermined, said percentage composition in regard to each component being within the range of not less than 20% and not more than 55% by volume and said addition being made so that the added aqueous alcohol solution is not less than one-half the weight and not more than

twice the weight of the neutralized sulphonate; (d) permitting said previously agitated diluted mass to separate into a three-layer system consisting of: (A) unreacted oil substantially free from mahogany acid sulphonates and peppery sludge; (B) an aqueous alcohol solution of petroleum sulphonates substantially free from unreacted oil, inorganic acid salts, and peppery sludge; and (C) a substantially concentrated inorganic salt brine containing loosely commingled peppery sludge; and (e) withdrawing said aforementioned (A) layer and (C) layer.

5. A process for producing petroleum sulphonates, characterized by subjecting non-pre-treated, Gulf coastal naphthene base, crude petroleum containing a significant amount of polymerizable constituents to the following procedure: (a) a sulphonation-polymerization step; (b) a washing step involving an aqueous vehicle and subsequent separation of dilute acid; (c) a neutralization-alcoholic solvent addition-extraction step involving neutralization by means of ammonium hydroxide and the addition of a predetermined amount of an ethyl alcohol-isopropyl alcohol-water mixture in which the percentage composition of the components has been predetermined, said percentage composition in regard to each component being within the range of not less than 20% and not more than 55% by volume and said addition being made so that the added aqueous alcohol solution is not less than one-half the weight and not more than twice the weight of the neutralized sulphonate; (d) permitting said previously agitated diluted mass to separate into a three-layer system consisting of: (A) unreacted oil substantially free from mahogany acid sulfonates and peppery sludge; (B) an aqueous alcohol solution of petroleum sulfonates substantially free from unreacted oil, inorganic acid salts, and peppery sludge; and (C) a substantially concentrated inorganic salt brine containing loosely commingled peppery sludge; and (e) withdrawing said aforementioned (A) layer and (C) layer.

6. A process for producing petroleum sulphonates, characterized by subjecting non-pre-treated, Gulf coastal naphthene base, crude petroleum containing a significant amount of polymerizable constituents to the following procedure: (a) a sulphonation-polymerization step; (b) a washing step involving an aqueous vehicle and subsequent separation of dilute acid; (c) a neutralization-alcoholic solvent addition-extraction step involving neutralization by means of ammonium hydroxide and the addition of a predetermined amount of an ethyl alcohol-isopropyl alcohol-water mixture in which the per-

centage composition of the components has been predetermined, said percentage composition in regard to each component being within the range of not less than 30% and not more than 40% by volume and said addition being made so that the added aqueous alcohol solution is not less than one-half the weight and not more than twice the weight of the neutralized sulphonate; (d) permitting said previously agitated diluted mass to separate into a three-layer system consisting of: (A) unreacted oil substantially free from mahogany acid sulphonates and peppery sludge; (B) an aqueous alcohol solution of petroleum sulphonates substantially free from unreacted oil, inorganic acid salts, and peppery sludge; and (C) a substantially concentrated inorganic salt brine containing loosely commingled peppery sludge; and (e) withdrawing said aforementioned (A) layer and (C) layer.

7. A process for producing petroleum sulphonates, characterized by subjecting non-pre-treated, Gulf coastal naphthene base, crude petroleum containing a significant amount of polymerizable constituents to the following procedure: (a) a sulphonation-polymerization step; (b) a washing step involving an aqueous vehicle and subsequent separation of dilute acid; (c) a neutralization-alcoholic solvent-addition-extraction step involving neutralization by means of ammonium hydroxide and the addition of a predetermined amount of an ethyl alcohol-isopropyl alcohol-water mixture in which the percentage composition of the components has been predetermined, said percentage composition in regard to each component being within the range of not less than 30% and not more than 40% by volume and said addition being made so that the added aqueous alcohol solution is not less than one-half the weight and not more than twice the weight of the neutralized sulphonate; (d) permitting said previously agitated diluted mass to separate into a three-layer system consisting of: (A) unreacted oil substantially free from mahogany acid sulphonates and peppery sludge; (B) an aqueous alcohol solution of petroleum sulphonates substantially free from unreacted oil, inorganic acid salts, and peppery sludge; and (C) a substantially concentrated inorganic salt brine containing loosely commingled peppery sludge; (e) withdrawing said aforementioned (A) layer and (C) layer, and subsequently employing distillation procedure to separate the alcohols in the (C) layer from the water and sulphonate mixture.

JOHN R. AVERILL,
EDWIN E. CLAYTOR.
